UNITED STATES PATENT OFFICE.

GEORGE ROSS AND STEPHEN F. DEAL, OF KANSAS CITY, MISSOURI.

TANDEM TAMPING-MACHINE.

No. 891,954.

Specification of Letters Patent.

Patented June 30, 1908.

Application filed February 24, 1908. Serial No. 417,329.

To all whom it may concern:

Be it known that we, GEORGE ROSS and STEPHEN F. DEAL, citizens of the United States, residing at Kansas City, in the county 5 of Jackson and State of Missouri, have invented certain new and useful Improvements in Tandem Tamping-Machines, of which the following is a specification.

This invention relates to tamping machines 10 of that character embodying peripherally toothed tamping wheels or members for tamping from the bottom upward as distinguished from the ordinary tampers which tamp from the surface downward and our object is to produce a machine of this character 15 provided with two tamping rollers each consisting of a series of toothed wheels or members and one adapted to be turned for the purpose of guiding the machine in the desired direction.

A further object is to produce a machine which can be converted from a tamping into a rolling machine and vice versa and which carries its own motive power.

With this general object in view the invention consists in certain novel and peculiar features of construction and organization as hereinafter described and claimed; and in order that it may be fully understood reference is to be had to the accompanying drawing, in which—

Figure 1, is a side elevation of an ordinary steam rolling machine equipped with tamping rollers embodying our invention in lieu of 35 the ordinary smooth rollers. Fig. 2, is an enlarged vertical section taken through the front or traction roller of the machine.

In the said drawing, 1 indicates the frame of the machine terminating at its rear end 40 in a gooseneck 2 and equipped with a boiler 3 and with an engine and other equipment not shown of a boiler for the purpose of developing the power necessary to propel the machine, this equipment corresponding to 45 that of an ordinary steam roller. The frame carries a water tank 4 and the tool box 5 as usual though by preference said parts will be detachable for the purpose of facilitating an exchange of rollers when necessary to convert 50 the machine from a tamping into a rolling machine and vice versa. At its rear end the machine is provided with the usual swivel yoke 6, equipped with a transverse

shaft 7 and at its front end the frame carries bearings 8 for a transverse shaft 9.

The tamping rollers 10 and 11 are of identical construction except that the former is smaller than the latter and certain of the wheels or members of the latter are rigidly secured upon their respective shaft in order 55 to obtain the necessary traction on the ground to propel the machine. Each roller consists of a series of peripherally toothed wheels or members comprising hubs 12, spokes 13, rims 14 of triangular form in cross 60 section and long teeth 15 projecting radially outward from the oblique outer faces of the rim, the teeth of one face being disposed alternately with respect to the teeth of the other when viewing the wheel or member 65 from the side. The wheels or members are arranged side by side and in roller 10 are capable of independent turning movement on shaft 7. The wheels or members of roller 11 are likewise arranged side by side on their 70 shaft 9, but in this roller a sufficient number of them to give the desired traction on the ground, are secured rigidly on the shaft, three being shown as secured rigidly on the shaft in Fig. 2, by means of screw bolts 16. 75

The teeth of the wheels or members of both rollers taper slightly toward their outer ends by preference in order that in the movement of the machine forward or backward they will withdraw their embedded faces from the 80 ground with but little if any tendency to lift or kick up the earth, it being understood that their outer faces or ends are sufficiently broad to perform a tamping as distinguished from a digging or plowing function. 85

The teeth of the tamping wheels or rollers being spaced apart tamp in spots, it being understood that the earth or other substance being tamped is in a soft or loose condition and because of this fact the teeth which by 90 preference in length will correspond to the depth of the loosened earth or substance, will be deeply embedded and thus act to each tamp a small part of such earth or substance down upon the solid earth or other 95 substance beneath. On each subsequent passage of the teeth they will press un-tamped portions down upon that previously tamped so that repeated passages of the teeth gradually superpose and compress together what may be termed tamped sections 100

or layers of the earth or other substance and eventually pack the entire mass solidly from the bottom upward as distinguished from the action of a plane or unbroken surfaced roller 5 which compresses from the top downward.

By the use of the toothed rollers the earth or other substance is thus packed solidly with a substantially uniform pressure whereas in the latter case the density of the packed 10 earth or other substance is greatest near the top and diminishes downwardly toward the underlying bed.

In the copending application filed in the names of Stephen F. Deal and George Ross 15 as inventors, Jan. 31, 1908, Serial Number 413,708, a single toothed tamping roller is disclosed consisting of the series of independently rotatable wheels or members and adapted to travel in one direction only, it 20 being necessary to finish the surface tamped by said roller with a smooth roller machine. This invention differs from that in that it embodies a pair of rollers one of which acts as a traction roller by having certain of its 25 wheels or members rigid with the shaft with the teeth of such rollers of such form that the machine can be run forward or backward without picking or kicking up the earth or other substance. This invention also differs 30 from that forming the subject of said copending application in that one of its toothed rollers can be turned for the purpose of guiding the machine in the desired direction it being further noted that in the guiding roller 35 10, all of the wheels or members are journaled on their supporting shaft so that in turning some of such wheels or members are capable of turning backward or at varying speeds according as the turn is sharp or 40 otherwise. In view of the fact that there is a relative movement between the contiguous wheels or members and also because of the triangular or wedge shaped rims, the earth or other substance will not become wedged or 45 packed in between their teeth and thus interfere with the proper tamping function, this being also true of the roller of the copending application.

In order that motion may be imparted to 50 the machine the end wheels or members of the front roller will be equipped with beveled gear wheels 17 to be engaged by the customary driving pinions, not shown of the ma-

chine, the rotation of these wheels imparting movement to the shaft 9 in order that the 55 central wheel or member shall also act to assist in propelling the machine.

From the above description it will be apparent that we have produced a tamping machine possessing the features of advantage 60 enumerated as desirable and we wish it to be understood that we reserve the right to make all changes falling within the spirit and scope of the appended claims.

Having thus described the invention what 65 we claim as new and desire to secure by Letters Patent, is:—

1. A tamping machine, comprising a suitable frame, a pair of rollers supporting the same and arranged tandem, one of the rollers 70 being swiveled to the frame, and consisting of a series of independently rotatable toothed wheels or members and the other of a shaft and a series of toothed wheels or members some of which are secured rigidly on the shaft 75 and others loosely thereon.

2. A tamping machine comprising a suitable frame, a pair of rollers supporting the same and arranged tandem, one of the rollers being swiveled to the frame, and consisting of 80 a series of independently rotatable toothed wheels or members and the other of a shaft and a series of toothed wheels or members, the outermost of which are secured rigidly on the shaft and provided at their outer sides 85 with gear wheels and others loosely on said shaft.

3. A tamping machine comprising a suitable frame, a pair of rollers supporting the same and arranged tandem, one of the rollers 90 being swiveled to the frame and consisting of a series of independently rotatable skeleton wheels or members provided with radial outwardly tapering teeth and the other of a shaft suitably journaled, a series of wheels or members journaled thereon, and a plurality of 95 wheels or members rigidly secured thereon, the said wheels or members being equipped with radial outwardly tapering teeth.

In testimony whereof we affix our signatures, in the presence of two witnesses.

GEORGE ROSS.
STEPHEN F. DEAL.
